UNITED STATES PATENT OFFICE.

JOHN F. WYNNE, OF ATLANTA, GEORGIA.

PERPETUAL CALENDAR.

1,275,350.

Specification of Letters Patent. Patented Aug. 13, 1918.

Application filed October 13, 1916. Serial No. 125,413.

To all whom it may concern:

Be it known that I, JOHN F. WYNNE, a citizen of the United States, and a resident of Atlanta, in the county of Fulton and

5 State of Georgia, have invented a certain new and useful Improvement in Perpetual Calendars, of which the following is a specification.

The present invention relates to 10 calendars, and particularly to that type known as perpetual calendars.

An object of the present invention is to provide a calendar of this character which is adapted for use as a daily, monthly, 15 yearly, and reference calendar, and a calendar which is of such a nature as to embody, in a simplified and compact structure, all of the principles or features of all prior calendars, and permit the rapid forward 20 and backward calculation of days, months and years.

The invention has for another object to 25 peculiarly construct the calendar for coöperation with novel tables of days, months and years to permit the rapid adjustment of the calendar for forward and backward calculation, and to ascertain quickly the exact day upon which the first of each month falls, and the exact number of days in each 30 particular month.

It is a further aim of the present invention to provide the calendar with means for singly and successively displaying days of each month and the dates thereof, and to 35 permit the inspection of the entire month calendar without disturbing the adjustment of the single day display devices.

The above, and various other objects and 40 advantages of this invention will be brought out more clearly in the following detailed description of the present preferred embodiment of this invention, the same being illustrated in the accompanying drawings wherein:

45 Figure 1 is a plan view of a calendar constructed according to the present invention, and being adjusted to disclose the date of one day only.

Fig. 2 is a similar view showing the calendar adjusted to display the days of an entire month.

Fig. 3 is a longitudinal section taken on the line 3—3 of Fig. 1, looking toward the top of the calendar.

50 Fig. 4 is a transverse section taken on the

line 4—4 of Fig. 1, showing the arrangement of the various slides employed.

Fig. 5 is a plan view, in detail, of the day slide.

Fig. 6 is a detail perspective view of one 60 of the cover strips.

Fig. 7 is a detail perspective view of the opposite cover strip.

Fig. 8 is a detail perspective view, enlarged, of two of the adjustable blinds, showing 65 the rear sides thereof, and the attachment of the blinds to the supporting rod therefor.

Fig. 9 is a detail perspective view of one 70 of the blinds, showing the pocket formed on the front face thereof for the reception of an advertising card or the like.

Fig. 10 is an enlarged fragmentary plan view of one end of the month slide.

Fig. 11 is an enlarged fragmentary view 75 of one end of the year slide.

Fig. 12 is a plan view of one of the posters or cards adapted to be secured to one side of the calendar, and showing the arrangement of the key number table.

Fig. 13 is a plan view of a second poster or card adapted for attachment to the face of the calendar, and showing the arrangement of the ordinary and leap year tables, and the century table.

Referring to these drawings, wherein like parts are designated by similar characters of reference throughout the several views, 80 15 designates the back, which may be made from heavy cardboard, or any other suitable stiff material. The back 15 is preferably of rectangular form and may be made of any size and provided with any suitable supporting or suspension devices according to the location in which it is desired to place 90 95 the calendar.

The back 15 is provided across its face, and at its lower edge, with a relatively narrow spacing strip 16, and is provided at its top edge and on its outer face with a second 100 spacing strip 17. The spacing strips 16 and 17 extend substantially throughout the entire length of the back 15, and provide, between the spacing strips, as shown in full and in dotted lines in Fig. 2, a longitudinally 105 extending guiding groove or recess into which is fitted a day slide 18. As shown in Fig. 5, the day slide 18 comprises a flat card of a width adapted to fit snugly in the guiding recess, and being of less length 110

than that of the back 15 to permit of the sliding of the day slide back and forth between the strips 16 and 17. The day slide 18 is provided, intermediate the ends thereof, with an outwardly projecting knob 19 adapted to be grasped in the fingers for operating the slide.

The day slide 18 is held in the guiding recess or groove by means of a pair of oppositely disposed partition plates 20 which are suitably secured across the spacing strips 16 and 17, adjacent to the opposite ends of the back 15. A sight-opening or space is thus provided between the inner opposite edges of the partition plates 20.

The day slide 18 is provided across its face, and adjacent to its upper edge, with a horizontal row of consecutively increasing numbers from one to seven, corresponding to the seven days of a week, the slide 18 being adapted for adjustment across the face of the back 15 to bring the numeral 1 immediately beneath any one of the horizontal rows of abbreviations 21 arranged across the lower edge of the spacing strip 17 in the sight opening. The day slide 18 is further provided with vertical and horizontal columns of consecutively increasing numbers which are so arranged that for any position of the slide 18 in the sight opening, the numbers will appear therein in consecutive order and indicate the dates of the various days of the selected month. When the slide 18 is adjusted into the position shown in Fig. 2, and it is desired to indicate a month having but 28 days, such as the month of February during ordinary years, a cover strip 22 is provided which is mounted to slide horizontally across the second lower row of horizontal figures of the slide 18. This cover slide or strip 22 is of a width equal substantially to the width of said horizontal row of numbers, and is fitted between a pair of spaced-apart guide strips 23 and 24 which are secured against the outer face of the partition plate 20. An outturned lip 25 is formed on the outer end of the slide strip 22 by means of which the cover strip may be drawn outwardly across the slide 18 to block off or cover the desired number of numerals in the horizontal column. This cover strip 22 is preferably located at the right-hand end of the calendar. A second cover strip 26, shown in detail in Fig. 6, is similarly mounted upon the face of the opposite partition plate 20 and is adapted to be drawn outwardly by means of a lip 27 across the lower horizontal column of figures on the day slide 18. As the slide 26 is located upon the left-hand end of the calendar, the same is provided with an aperture or opening 28 located inwardly from the end of the strip 26 a distance equal to the width of one of the vertical columns on the slide 18. The slide 26

may be drawn outwardly across the lower horizontal row of numbers on the slide 18 to cover the outermost number and to disclose the next adjacent number through the opening 28.

The back 15 further supports a pair of face plates 29 and 30 of substantially the same size as the partition plates 20, and being arranged immediately over the same to cover the partition plates, and to hold the slides 22 and 26 in place. As shown in the drawings, staples 31 are employed for securing the face plates, and the partition plates to the back 15.

At the top of the calendar, between the back 15 and the top strip 17, are arranged two slides, a year slide 32, and a month slide 33. These slides are each in the form of a long strip of a length substantially one-half that of the back 15, and provided at one end with an outwardly extending knob 34 projecting through a longitudinal slot 35 formed for each slide, and by means of which each slide is guided in its horizontal path. As shown in Fig. 10, the month slide 33 is provided with a longitudinal row or column of indicia designating consecutively the months of the year, and beneath each month the number of days in said month. In Fig. 11 there is shown one end of the year slide 32, and from which it will be noted that the slide has upon its face numerals designating consecutively a number of years, and giving immediately below each year a key number for a purpose which will hereinafter appear. The strip 17 is provided, at the inner ends of the slot 35, and immediately over the sight opening for the day slide, with vertically spaced-apart sight openings 36 and 37 through which may be viewed, respectively, the year with its key number, and the month with its number of days.

An open preferably rectangular frame 38 is hinged at one end vertically upon the face plate 29 adjacent to the inner edge of the latter, and is adapted to be swung across the sight opening of the slide 18 and to engage at its free end the opposite face plate 30. A thumb nut 39 or the like is mounted on the face plate 30 and is adapted for engagement with the free end of the frame 38 to hold it across the slide 18. The frame 38 is provided with a plurality of vertically spaced-apart rods 40 which extend horizontally across the frame 38 and are secured to the opposite ends thereof. Any number of these horizontal rods 40 may be provided in the frame 38, preferably one rod for each horizontal row of numbers upon the slide 18. Slidably mounted on the rods 40 are a plurality or series of blinds 41 of a width and length corresponding to the width and length of each number on the slide 18, and adapted to cover the numbers

on the slide 18 from view. When the frame 38 is swung into closed position, shown in Fig. 1, the blinds 41 normally cover all of the numbers on the face of the slide 18 which appear in the sight opening. In this figure, the number 19 in the second vertical column of the day slide is disclosed. To effect this, the first slide 41 on the fourth rod 40 is slid into the left-hand end of the frame 38 to first uncover the numeral 18. The next adjacent slide 41 is now moved leftward, to cover the number 18 and to disclose the number 19 as shown. In a like manner, each successive blind 41 may be slid to the left to uncover each successive number and to hide the date of the day preceding. When the lowermost column of figures on the day slide 18 appears in the sight opening, the cover plate 26 may be operated to disclose but one of the numbers at a time, and the blinds 41 may all be retained in normal position.

As shown to advantage in Figs. 8 and 9, each blind may be in the form of a relatively flat plate having its upper edge rolled over to provide a sleeve 42 for sliding engagement on the rod 40. The end and bottom edges of the plates are rolled over forwardly to provide spaced flanges 43 behind which may be slid a card 44 or the like bearing an advertisement. This calendar is adapted particularly for use in hotels, banks, public offices and the like, and the blinds 41 provide neat and attractive means for holding a relatively large number of display cards.

The face plates 29 and 30 may be provided with posters or cards 45 and 46 to which the key numbers on the slide 32 refer. The card 45 is provided with a key-number table, and is provided with vertical columns of numbers indicating consecutively the years beginning with 1600 and ending with 1999. Each year number is provided with a key number, the key numbers running from 1 to 14 inclusive, and corresponding with and supplementing the year slide 32. Across the lower end of the card 45 may be placed a legend explaining the purpose and use of this table.

The card 46 is provided upon its face, and at its top, with an ordinary year table divided into seven columns corresponding to seven of the key numbers above referred to. These columns are arranged vertically, and in each are the names of the twelve months followed by the names of the days on which the first of each month falls. Thus, if the key number is three, upon reference to this ordinary year table, it will be found out that the first of June falls upon Saturday. Upon reference to the key number table, it will be found that the year 1907 is followed by the key number three. Therefore, in 1907 the first of June falls on Saturday.

The card 46 is also provided with a leap year table divided into seven vertical columns headed by the key numbers eight to fourteen inclusive. These columns are arranged similar to the columns at the top of the card 46, and contain the names of the months consecutively arranged therein and followed by the names of the days upon which the first of the respective months falls. If the key number table on the card 45 shows that the predetermined year is followed by a key number from eight to fourteen, it is then known that the year is a leap year, and upon reference to the leap year table the day upon which the selected month falls will be readily found. These key number columns on the card 46 determine the position in which to adjust the slide 18 so as to place the numeral one thereof beneath the designated day of the fixed column carried in the sight opening.

The card 46 is further provided, preferably near its lower end, with four columns of numbers headed by century numbers, such as 1600, 1700, 1800 and 1900. A suitable legend is placed at the lower end of the card 46 to explain the use of this century table. In the 1600 column are placed century numbers which are four hundred years apart, and which therefore have the same key number as the century number 1600 at the top of its column. For instance, should it be desired for any purpose to ascertain upon what day the first of March 2006 would fall upon, it would be necessary to refer to the year 1600 which appears at the top of the first century column, and to trace the year 1606 upon the key number table on the card 45, and it will be found that the key number of such year is one. Referring now to the first key number column on the card 46, it will be found that the first of March of the said year falls upon Wednesday. The month slide 33 indicates below the name of each month the number of days therein, and this slide may be manipulated to calculate the exact number of days between any given period. It is of course understood that the details of construction of this calendar may be modified and changed to adapt the same to various conditions of use without departing from the spirit of this invention, and being restricted only by the scope of the following claims.

I claim:

1. In a calendar, the combination of a body portion having day, month and year tables arranged thereon with key numbers, a year slide on the body portion having key numbers thereon corresponding to the years and to said tables and adapted to be adjusted accordingly, a month slide on the body portion having numbers thereon corresponding to the number of days in the respective

months and adapted to be adjusted according to the tables, and a day slide having day numbers thereon adapted to be adjusted according to the table and month slide indications.

2. In a calendar, the combination of a body portion provided with tables thereon arranged according to key numbers, a year slide mounted on said body portion and bearing year numbers with corresponding key numbers arranged immediately therebeneath and adapted to be disclosed one at a time, said key numbers on the year slide being arranged in said tables to indicate the day of the week upon which the first of each month falls, and a day slide arranged on said body portion and bearing columns of consecutively arranged numbers indicating the days of a month and adapted to be adjusted according to the showing of said tables.

3. In a calendar, the combination of a body portion having rows of tables thereon arranged according to key numbers, a year slide mounted on said body portion and having various years marked thereon and key numbers beneath said years according to said tables, said body portion also having a column of consecutively arranged days of the week, and an adjustable slide having columns of consecutively arranged numbers indicating the days of a month and adapted for adjustment beneath said column of days of the week according to the showing of said tables.

4. In a calendar, the combination of a body portion provided with tables on the face thereof arranged according to key numbers, and having a column of days of the week arranged consecutively across the face of the body portion, a year slide mounted upon the body portion, said body portion having a sight opening therein adapted to disclose the years on said year slide one at a time, the years on the year slide each having a key number corresponding thereto and arranged therebeneath, and a day slide provided with columns of numbers indicating the days of the month and adapted for adjustment relatively to said days of the week column according to the showing of said tables as indicated by said key numbers.

5. In a calendar, the combination of a body portion provided with tables thereon arranged according to key numbers, a year slide mounted on said body portion and bearing year numbers with corresponding key numbers arranged immediately beneath and adapted to be disclosed one at a time with the year numbers, said key numbers on the year slide being arranged in said tables to indicate the month and the day of the week upon which the first of each month falls, a day slide arranged on said body portion and bearing columns of consecu-

tively arranged numbers indicating the days of a month and adapted to be adjusted according to the showing of said tables, and a month slide having numbers beneath the month indications thereon indicating the number of days in the respective months and adapted to be adjusted according to the tables to indicate the month of the year and to correspond to the adjustment of the day slide.

6. In a calendar, the combination of a body portion provided with day, month and year tables and key numbers therefor, and having a relatively large sight opening, and two smaller sight openings, said body also having a row of days of the week arranged consecutively across the relatively large sight opening, a day slide adjustably mounted on the body portion and bearing columns of numbers adapted for adjustment according to said tables in said relatively large sight opening beneath the rows of days of the week to show the day upon which each first of month falls and the numbers of the succeeding days, a year slide mounted on said body portion and bearing year numbers and corresponding key numbers adjacent thereto adapted to be viewed one at a time through one of said smaller sight openings, said key numbers on the year slide being adapted to indicate on said tables the adjustment for said day slide, a month slide mounted on the body portion and bearing the months of each year with the days of each month arranged adjacent thereto and adapted to be disclosed in the second one of said smaller sight openings, and means for blocking off the numbers on said day slide to adjust the latter according to the reading on said month slide.

7. In a calendar, a body portion having month and day tables thereon, a slide in the body having a plurality of horizontal row of consecutively increasing numbers indicating the days of a month and adapted to be adjusted according to said tables, a month slide mounted on said body portion and bearing the names of the months and the numbers of days beneath the name of each respective month and adapted to be adjusted according to said tables, a covering slide arranged at the right side of said first slide and adapted to cover an adjacent number in the second last row of the same, and a second covering slide adjustable at the left side of the body portion and adapted for adjustment over the two adjacent numbers of the last row of the same, said second covering slide being provided with an opening intermediate its ends adapted to close the adjacent end number of the last row and to cover the second adjacent number, said covering slides being adjustable according to the number of days indicated on said month slide.

8. In a calendar, a body portion having a key number table thereon formed of columns of year numbers having key numbers having corresponding positions opposite to the year numbers, and having a century table including columns of predetermined period years corresponding to the tabulated years in the key number table, a year slide adjustably mounted on said body portion and having 5 years marked thereon with corresponding key numbers adjacent to each year and adapted to be disclosed one at a time on the body portion, said body portion being also provided with tables comprising vertical 10 columns of months and days arranged ac- 15

cording to the key numbers and adapted to indicate the day upon which the first of each month falls under the given key number, said body portion being also provided with a horizontal row of consecutively arranged days of the week, and a day slide adjustable upon the body portion beneath said horizontal rows of days of the week and bearing vertical columns of numbers indicating the number of days in a month and 20 adapted for adjustment beneath the horizontal day column according to the showing of said year tables. 25
